UNITED STATES PATENT OFFICE.

FREDERIC E. GARDNER, OF BELOIT, WISCONSIN.

GRINDING MACHINE.

Application filed June 20, 1921. Serial No. 478,830.

To all whom it may concern:

Be it known that I, FREDERIC E. GARDNER, a citizen of the United States, residing at Beloit, in the county of Rock and State of Wisconsin, have invented certain new and useful Improvements in Grinding Machines, of which the following is a specification.

My invention relates to grinding machines and particularly to that type comprising a rapidly revolving grinding disk and a revolving work carrier on which objects to be ground are secured to be successively carried into grinding relation with the grinding wheel.

One of the important objects of my invention is to provide simple, economical and efficient construction in which the axes of the grinding element and the work carrier are vertical, and with the grinding element above the carrier so that work is applied by the carrier against the under side of the grinding element.

Another important object of the invention is to provide improved means for adjusting the distance between the axes of the carrier and grinding element to obtain the desired degree of overlap and the best relative position for application of work to the grinding element.

A further object is to provide means for readily adjusting the grinding element vertically.

A further object is to provide simple and efficient means for yieldably applying work against the grinding face after such work has been brought into the grinding field by the carrier.

The above and other features of my invention are disclosed in the machine shown on the accompanying drawing, it being understood, however, that changes and modifications could readily be made which would still come within the scope of my invention.

On the drawings—

Fig. 1 is a side elevational view.

Fig. 2 is a front elevational view.

Fig. 3 is an enlarged sectional view on plane 3—3, Fig. 2.

Fig. 4 is an enlarged plan view of the work carrying frame with parts broken away.

Fig. 5 is an underside view of the work carrying frame with parts broken away.

Fig. 6 is an enlarged sectional view on plane 6—6, Fig. 1, and

Fig. 7 is an enlarged sectional view on plane 7—7, Fig. 2.

Generally describing the machine, it comprises a grinding disk arranged to revolve on a vertical axis, below which disk a work carrier frame is arranged to revolve on a vertical axis, the axes being offset so that the disks and carrier overlap only partially. On the carrier are mounted a series of work holding tables which are successively raised by cam mechanism to present supported work to the grinding surface. The carrier structure is adjustable toward or away from the grinding axis and the grinding wheel is vertically adjustable.

The driving trains for the grinding and carrier elements are arranged within the base frame 10, the pedestal frame 11 and the top frame 12 detachably connected together as shown in Fig. 1. In the journal boxes 13 and 14 on the base frame is journaled the main driving shaft 15 driven by a pulley 16 with belt or otherwise. At the inner end of the drive shaft is the bevel pinion 17 which meshes with the bevel gear 18 on the countershaft 19 journaled in the base frame at right angles with the shaft 15. At its outer end the countershaft carries the spur pinion 20 which meshes with the spur gear 21 rotatable idly on a second countershaft 22 and adapted to be connected in driving relation with said shaft by suitable clutch mechanism 23 operated from the front of the machine by means of the lever 24. At the front of the machine and parallel with the countershaft is the worm shaft 25 which is journaled at its left end in bearings 26 and 27 provided in the lower ends of the arms 28 and 29 depending from the base 30 on which the work carrier frame R is supported. At

its right end the shaft 25 is slidable in but splined to the hub 31 which has bearing in the journal boxes 32 and 33 provided in the base frame 10. Keyed on the hub are the spur gears 34 of different diameters for meshing with suitably sized gears 35 detachably secured on the outer end of the

countershaft 22. A cover 36 is provided on the base frame so that ready access may be had for applying suitable gears on the shaft 22 to get the desired speed transmission 5 from the shaft 15 to the countershaft 25.

Between the bearing boxes 26 and 27 the shaft 25 carries a worm 37 which meshes with the worm wheel 38 secured to the lower end of the vertical shaft 39. This shaft has 10 bearing in the sleeve 40 forming part of the base 30 and at its upper end has the gear pinion 41 which meshes with the gear 42 secured to the hub 43 of the work carrier R. This hub has bearing engagement with the 15 top of the base 30 and also with the vertical stub shaft 44 secured to and extending upwardly from the base 30. A threaded nut 45 engages the upper end of the shaft to lock the carrier on the base. 20 As best shown in Figs. 2 and 7, the base frame 10 has the parallel upstanding walls 46 and 47 provided with horizontal flanges 48 and 49 on which the base 30 seats and is 25 slideable, strips 50 and 51 being secured to the base and engaging with the under sides of the flanges to thereby hold the base on its guideways. The base 30 is thus shiftable laterally and is held in adjusted position by screws 52. During adjustment of the base 30 the shaft 25 slides in the hub 31.

The work carrier R has the top and bottom walls 53 and 54 and the circular or cylindrical wall 55. At intervals the circular wall is deflected outwardly to provide 35 pairs of flanges 56 and 57, each pair forming guides for a work holding table 58, the tables being slideable transversely on the carrier parallel with its axis. Each table has strips 59 and 60 secured thereto which engage 40 against the under sides of the flanges to lock the table thereon. Each table between its supporting flanges has depending walls 61 and 62 whose inner ends are connected by a plate 63, the walls and plate together with 45 the body of the table forming a rectangular passageway for a cam head 64 which is bifurcated to receive a cam roller 65. At its upper end each table has a lug 66 in which is threaded an abutment bushing 67. The 50 stem 68 extending from the cam head is guided in the lug 69 on the circular wall of the carrier frame, the upper end 70 of the stem being of reduced diameter and extending into the bushing 67, a compression spring 71 encircling the stem between the bushing and the washer 72 engaging on the stem and against the shoulder 73. A washer 74 is preferably inserted between the spring and the bushing, and normally when the cam 55 roller is disengaged the table with the cam block and stem thereon is supported on the lug 69 through the spring and the washers. 60

On top of the base 30 is the cam rail 75 which is successively engaged by the cam rollers of the various work holding tables,

engagement of a cam roller with the rail causing the respective cam block and its stem to be raised, such raising movement being communicated by the washer 72 to the spring 71 and through the bushing 67 to 70 the respective work holding table so that work secured to the table will be raised into position to be engaged by the grinding mechanism which will now be described. By means of the spring the work is yieldably 75 applied to the grinding element, the spring protecting the carrier against shocks and strains due to any irregularities in the grinding.

In the front housing frame 12 are the upper and lower journal box structures 76 and 77 for journaling the vertical shaft 78 on the lower end of which is secured the head 79. By means of screws 80 a circular plate 81 is secured to the head concentric with the shaft 78 and on the sides of this head are secured annular grinding disks 82 and 83. The plate 81 may be reversed on the head 80 so that after one of the grinding disks is worn away the other disk may be presented. The housing frame 12 is vertically shiftable on the ways 84 provided on the pedestal frame 11. At the upper end of the pedestal frame is journaled the vertical shaft 85 which may be turned by the hand wheel 86 95 and whose lower end is threaded to engage in the lug 87 extending from the frame 12. By means of this shaft the frame 12 may be raised or lowered.

Secured to the grinding wheel shaft 78 is the bevel gear 88 with which meshes the bevel pinion 89 on the front end of the horizontal shaft 90 which is journaled in the extension 91 on frame 12 and which at its rear end carries the gear pinion 92. The rear end of the extension 91 supports the bearing housing 93 in which is journaled the vertical hub 94 in which the vertical shaft 95 is splined. Secured to the hub is the bevel gear 96 which meshes with the pinion 92. At its lower end the shaft 95 has bearing in the journal box 97 supported on the base frame 10 and has the bevel pinion 98 thereon which meshes with the bevel gear 18 which is driven from the main shaft 15. The grinding element is thus driven from the main shaft 15 and during vertical adjustment of the supporting framework 12 the hub 94 slides along the shaft 95.

The vertical shafts 44 and 78 of the carrier frame and grinding wheel respectively are offset laterally a distance so that the carrier frame and grinding disks overlap only partially, the carrier frame during rotation carrying work on the holding tables across the grinding disk near the periphery thereof where the grinding speed and other conditions are most efficient. As already described, the base 30 for the work carrier structure is shiftable laterally so that the 120

area of application for work supported on the carrier may be adjusted for. Under certain conditions as, for example, where irregular work has parts which will project

5 across the top of the holding tables to be ground, the frame 12 would be raised to vertically adjust the grinding disk the proper distance for efficient grinding. Such adjustment is quickly accomplished by turning the hand wheel 86.

10 The workman stands in front of the machine and owing to the slow speed of the work carrier structure he can readily apply work to the tables during operation of the machine. Usually fixtures are permanently secured to the tables in which fixtures the objects to be ground can be quickly and accurately clamped by the operator. As the carrier revolves the respective cam rollers

15 engage with the cam rail so that the holding tables are yieldably raised to present the supported work against the grinding disk. Owing to the comparatively high speed of the grinding element, grinding is rapidly

20 accomplished. After the grinding disk on one side of the supporting plate 81 is worn out the plate is reversed to present the opposite grinding disk. During a grinding operation the work is pressed yieldably 25 against the grinding face by the springs 71, and I provide means for stopping further travel of the tables as soon as the proper degree of grinding has been accomplished.

30 Referring to Fig. 1, each table is provided 35 with a lug 99 through which threads a micrometer screw 100 which can be readily turned by its knurled head 101 and which has a gauge dial 102 thereon with which a pointer 103 cooperates. On the carrier an

40 abutment lug 104 is provided for each micrometer screw. The various micrometer screws are set by the workmen according to the depth of grind desired and after a micrometer screw reaches its abutment grinding will stop. The length of the cam rail 45 is such that the tables are not raised until the work thereon is in position below the grinding disk. After a grinding operation the rollers leave the rail and the tables drop 50 to their normal position, the finished work being then removed therefrom by the operator.

55 My improved machine is of simple, rigid and efficient construction. All the parts are amply protected by the various housings. The grinding element, except for the grinding area, is enclosed in a housing 105 which may be connected by pipe 106 with a suitable suction device (not shown) for conveying away the grinding dust.

60 I claim as my invention:

1. A grinding machine having, in combination, a grinding wheel mounted to rotate on a vertical axis; a work carrier mounted to revolve on a vertical axis below said

grinding wheel, a work holding table vertically reciprocable on said carrier, a fixed lug on said working holding table, a lug on said carrier, a spring between said lugs normally tending to hold said table in work 70 receiving position, and means for compressing said spring to shift said table and said first mentioned lug toward the grinding wheel.

2. In a grinding machine of the class described, the combination of a grinding wheel adapted to be rotated on a vertical axis, a revolvable work carrier below said grinding wheel adapted to revolve in a horizontal plane and having longitudinal guides on its periphery, work holding tables reciprocable on said guides to present work to the grinding wheel as the carrier revolves, and means for shifting said tables toward the grinding wheel when the work is in grinding position. 75

3. In a grinding machine of the class described, the combination of a grinding wheel adapted to rotate on a vertical axis, a work carrier, a series of work holding tables shiftable on the periphery of said carrier, said carrier being rotatable about a vertical axis to successively present said tables in grinding position below said grinding wheel, and abutment mechanism operative to shift said 90 tables toward the grinding wheel when in grinding position whereby work thereon will be ground. 95

4. In a grinding machine of the class described, the combination of a grinding wheel adapted to rotate on a vertical axis, a work carrier, a series of work holding tables shiftable on the periphery of said carrier, said carrier being rotatable about a vertical axis to successively present said tables in grinding position below said grinding wheel, and yielding abutment mechanism operative to shift said tables toward the grinding wheel when in grinding position whereby work thereon will be ground. 100

105 5. A grinding machine having, in combination, a grinding wheel, a work carrier rotatable about a vertical axis, a lug on the periphery of said carrier, a supporting table mounted on the periphery of said carrier over said lug for vertical reciprocation, an inwardly extending lug on said table, a cam engaging member extending through said lugs and having a shoulder normally engaging said first mentioned lug, a spring on said cam engaging member between said lugs, and cam means for raising said member to compress said spring whereby said table is shifted toward said grinding wheel. 115

120 6. In a grinding machine of the class described, the combination of a grinding wheel, a work carrier having a cylindrical wall rotatable on a vertical axis below said grinding wheel, outward deflections on said wall having flanges which constitute guides 125 130

work holding tables vertically reciprocable on said guides for supporting work to be carried to the grinding wheel by the carrier, a yieldable abutment for each table, and a fixed abutment with which said yieldable abutments successively engage during rotation of the carrier, engagement of the abutments causing the respective tables to be raised to apply work thereon to the grinding wheel.

7. In a grinding machine of the class described, the combination of a supporting base, a vertical frame on one end of said base, a housing frame supported on said vertical frame and overhanging the other end of said base, a vertical shaft journaled in said housing frame, a grinding wheel supported thereon, a work carrying drum having a vertical spindle mounted in said base below said housing frame, a single power means operatively connected to said vertical shaft and said vertical spindle, means for varying the velocity ratio of said vertical spindle with respect to said vertical shaft, means for disconnecting said vertical spindle from said source of power, and means for adjusting said work carrying drum laterally to vary the degree of overlap between said drum and said grinding wheel without breaking said power connection.

8. In a grinding machine of the class described, the combination of an enclosing frame, a pair of spindles mounted in said frame, said spindles carrying operative elements arranged in overlapping position, a horizontal power shaft operatively connected with one of said spindles, a parallel shaft geared to said first mentioned shaft, another parallel shaft geared to said other spindle, speed change mechanism connecting said last mentioned shaft to said second mentioned shaft, said last mentioned shaft being capable of longitudinal adjustment without breaking said power connection, and clutch means for breaking the power connection to said last mentioned spindle, said machine frame serving to completely enclose all said shafts, connections and means.

9. A grinding machine having, in combination, a supporting base, a vertical frame on one end of said base, said frame supporting a grinding wheel mounted for rotation about a vertical axis, a work carrying drum mounted on said base below said grinding wheel for rotation about a vertical axis, said drum and said wheel being arranged in overlapping position, a plurality of vertically reciprocable work holding tables mounted on the outer periphery of said drum, actuating means located within said drum on the inner side of each table for actuating the latter as it is carried across the face of said grinding wheel, said tables

being constructed on their outer faces with a plurality of slots for supporting work blanks, and means within said frame and base for driving said grinding wheel and said drum in synchronous relation.

10. A grinding machine of the class described, having, in combination, a supporting base, a vertical frame on said base, a housing frame vertically adjustable on said frame and overhanging one end of said base, a grinding wheel supported on said housing for rotation about a vertical axis, a horizontal frame on the other end of said base, a work carrier supported on said horizontal frame for rotation about a vertical axis, said carrier being below said grinding wheel and partially overhung thereby, a main drive shaft journaled in said base, a horizontal shaft geared to said drive shaft below said vertical frame, a horizontal shaft extending below said work carrier and being geared to said first mentioned horizontal shaft, a vertical work carrier spindle geared to said last mentioned horizontal shaft, a vertical shaft in said vertical frame geared to said first mentioned horizontal shaft, a vertical shaft supporting said grinding wheel, and a horizontal shaft in said housing frame geared to both vertical shafts to effect a connection therebetween.

11. In a grinding machine of the class described, the combination of a supporting base, a vertical frame on one end of said base, a housing frame supported on said vertical frame and overhanging the other end of said base, a vertical shaft journaled in said housing frame, a grinding wheel supported thereon, a work carrier having a vertical spindle mounted on said base below said housing frame, a vertical shaft in said vertical frame, a horizontal shaft in said housing frame and connecting said vertical shafts, a main drive shaft journaled in said base, and means within said base for connecting said vertical spindle and said last mentioned vertical shaft to said main drive shaft.

12. In a grinding machine of the class described, the combination of a supporting base, a vertical frame on said base overhanging one end thereof, a grinding wheel supported on said vertical frame for rotation about a vertical axis, a horizontal frame on the other end of said base, a work carrier revolvable on said horizontal frame about a vertical axis, said carrier being below said grinding wheel and partially overhung thereby, work holding sections on said carrier shiftable vertically on the outer periphery thereof, said sections being successively carried into position below said grinding wheel during rotation of said carrier, means for raising said sections when traveling below said grinding wheel whereby work thereon will be applied to the grinding

wheel to be ground, and means for shifting said horizontal frame on said base to thereby adjust the degree of overhang of said grinding wheel with reference to said carrier.

13. In a grinding machine of the class described, the combination of a supporting base, a vertical frame on said base overhanging one end thereof, a grinding wheel supported on said vertical frame for rotation about a vertical axis, a horizontal frame on the other end of said base, a work carrier revolvable on said horizontal base about a vertical axis, said carrier being below said grinding wheel and partially overhung thereby, work holding sections on said car-

rier shiftable vertically on the outer periphery thereof, said sections being successively carried into position below said grinding wheel during rotation of said carrier, 20 means for raising said sections when traveling below said grinding wheel whereby work thereon will be applied to the grinding wheel to be ground, means for shifting said horizontal frame on said base to thereby 25 adjust the degree of overhang of said grinding wheel with reference to said carrier, and means for bodily vertically adjusting said grinding wheel.

In testimony whereof, I have hereunto set 30 my hand.

FREDERIC E. GARDNER.
